METHOD AND APPARATUS FOR HUMIDIFYING HYDROPHILIC MATERIALS

Stewart W. Speers, Upper Darby, Pa., assignor to FMC Corporation, Philadelphia, Pa., a corporation of Delaware

Filed Dec. 9, 1964, Ser. No. 417,007
13 Claims. (Cl. 34—23)

This application is a continuation-in-part of my application Ser. No. 396,165, filed Sept. 14, 1964, and now abandoned.

This invention relates to an improved method and apparatus for applying moisture to traveling hydrophilic materials, and especially for humidifying running webs of sheet materials.

Various materials and articles containing moisture lose moisture during manufacture, conversion and use so that moisture has to be restored to facilitate their handling and use. For example when paper and cellophane are manufactured, it is frequently not possible to control the drying of the sheet so that the moisture content of the product has the desired value. When paperboard is to be creased and folded for box manufacture, the moisture content must be controlled or otherwise the board may crack. Paper caps and paper containers must have a regulated moisture content to enable them to have required dimensions. Further, textile fabrics, leather and the like must have controlled moisture content for proper finishing, cutting and sewing. In addition when any of the hydrophilic materials is printed or coated with inks or lacquers that require heat for hardening and drying, there is always a loss of moisture in the base material which must be restored.

Generally, satisfactory humidification of hydrophilic materials can be achieved with methods and apparatus as described in my U.S. Patents 2,906,205 and 2,973,635 and the U.S. patent to J. D. Conti 2,718,065. However, when such known systems are employed for restoring large quantities of moisture and/or when high speed humidifying operations are attempted, the generally fragile material must often make more than one pass through the humidifying treatment and/or a comparatively large and expensive humidifying apparatus is required.

Attempts to compensate for the inadequacies of the known humidifying systems by surface wetting of the hydrophilic materials before and as they enter the humidifying apparatus have not proven to be successful. For example, prewetting of the hydrophilic material by means of a water bath provided only a negligible improvement in the amount of water retained by the material and was often accompanied by non-uniform humidification. On the other hand, water sprayed onto the hydrophilic material as it entered the humidifying apparatus "flashed off" before it had an opportunity to penetrate, while water sprayed into the steam atmosphere within the humidifying apparatus resulted in excessive and undesired water spotting of the material. Accordingly, a primary object of this invention is to provide an improved and more satisfactory method and apparatus for humidifying hydrophilic materials.

Another object of this invention is the provision of an improved method and apparatus for rapidly and uniformly imparting moisture to hydrophilic materials.

Still another object is the provision of an improved method and apparatus for imparting comparatively large quantities of water to hydrophilic materials which are moving at high speeds and without involving any water-spotting thereof.

These and other objects and advantages will be apparent from the following description.

2

FIGURE 1 is a vertical section taken longitudinally through the humidifying apparatus of the present invention;

FIGURE 2 is a transverse section taken along the line II—II of FIGURE 1; and

FIGURE 3 is an end view of the apparatus shown in FIGURE 1.

These objects are accomplished in accordance with the present invention by a method and apparatus wherein water in the form of a fine mist is applied on and adjacent to a hydrophilic material after which the material, along with the layer of water mist is passed into and through a generally confined area or chamber where it is subjected to a humid vaporous medium or atmosphere, such as wet or moist steam. This humid vaporous medium travels concurrently with the hydrophilic material and, in addition to itself imparting moisture to the material, causes the applied accompanying layer of water mist to penetrate rapidly and be absorbed into the material. This humidified hydrophilic material is then separated from the spent and excess humid vaporous medium and saturated air at it leaves the chamber and is rapidly cooled by the ambient atmosphere or a chill roll so as to retain the moisture which it has assumed.

In lieu of or in addition to the initial application of the fine water mist, the hydrophilic material may be subjected to a fine mist of water as it leaves the humidifying chamber and before it has been cooled. In both of these instances the hydrophilic material would pass through the humid vaporous medium and would therefore be in a hot or warm condition when it leaves the chamber. It was expected that the water mist provided at this location might perhaps be drawn into the area at which the humidified material is separated from the spent and excess humid vaporous medium and thus be removed before it has any opportunity to provide any benefit. Further, it was expected that any of such water mist which might settle upon the humidified material would result in water spotting and other signs of non-uniform humidification. Surprisingly, however, it was found that the water mist applied to the humidified material at this location was rapidly and uniformly assumed and retained by the material.

In general, the moisture content of the humidified material is greater when the water mist is applied before rather than after such material leaves the humidifying chamber. The most significant advantage, however, is that large quantities of moisture, such as 10% to 12% and more can be introduced into a hydrophilic material when such material is treated with mists of water both as it enters and leaves the humidifying chamber. The introduction of such large quantities of moisture is not accompanied by any water spotting or other signs of non-uniform application. Moreover, the modified procedure is efficient and economical since the residual heat of the humidified material is utilized, and thus dissipated, as it assists the last applied mist of water in penetrating into the material.

The apparatus of the present invention includes a chamber having separate and spaced entrance and exit openings for the hydrophilic material to pass therethrough and means, such as an atomizer, for applying water in the form of a mist on and adjacent to at least one side of the material as it approaches and enters and/or as it leaves the chamber. Within the chamber supply means, including a series of nozzles or jets, are provided for directing a humid vaporous medium toward the hydrophilic material. Exhaust or suction ducts are positioned within the chamber, along the opposite sides of its exit, for separating and removing the spent and excess humidifying medium and saturated air from along side of the humidified material as the latter leaves the chamber.

For satisfactory practice of the method of the invention, it is essential that water, in the form of a mist or fog, be applied to the hydrophilic material while such material is outside of the humidifying chamber. Any attempt to spray water within the chamber would result in condensation on the material which is being treated. Secondly, it is necessary that at least one layer of water mist accompany the hydrophilic material as it enters into and travels within the humidifying chamber and/or immediately after such material leaves the chamber. This is, of course, achieved by drawing such layer of water mist into the chamber by the exhaust or suction ducts which are located adjacent to the chamber exit opening.

The method and apparatus of the present invention are adapted for use with a variety of hydrophilic materials, such as paper and paperboard, whether made by the kraft or sulfite or other process, also glassine, textiles containing hydrophilic fibers, and other hydrophilic films, as for example films made from cellophane and cellulose ethers of the alkali-soluble or water-soluble type, alginates, casein, glue and the like. The material to be treated, which is referred to in the following detailed description as a "sheet material," may be in the form of a web, tube, band, ribbon, strip or in the form of individual sheets, pieces, parts, bags, shaped bodies and laminated structures formed in whole or in part of any of the moisture-containing materials noted above. In the latter instance, in which individual articles are being humidified, the articles are preferably carried upon a conveyor or similar device.

The apparatus of the present invention may be employed by itself or in combination with other equipment which performs such operations on the hydrophilic material so as to require humidification or rehumidification thereof to render the material suitable for its intended use or for further processing. For example, this humidifying apparatus may be used alone in adjusting the moisture content of a hydrophilic material which has been subjected to varying conditions during transit or storage. Alternatively, the humidifying apparatus may be employed with other equipment such as a conventional drying or coating system for reintroducing moisture into a material.

Referring now to the drawing the apparatus of the present invention includes a chamber 15 having top and bottom walls 17 and 19, side walls 21 and 23 and end walls 25 and 27. An entrance opening to the chamber is formed at 29 in the end wall 25 and a similar but separate exit opening is provided at 31 in the end wall 27. The sheet material which is to be humidified is indicated at 33 and is guided to and from the chamber 15 by rolls 35, 36 and 37, the latter of which may be chilled to rapidly cool the sheet material 33.

Positioned outside of the chamber 15, along one end perhaps both sides of the path of the sheet material 33, is an atomizer 39 which is connected by pipes 41 and 43 to suitable sources of water and air or other gas. The atomizer 39 provides an extremely fine and generally uniform mist or fog of water on or adjacent to the sheet material 33. With sheet materials of substantial width a plurality of such atomizers are preferably employed for laying a water mist along one or both sides of a sheet material, as illustrated in FIGURE 3. Of particular importance is that the water which is directed toward and intended to be applied to the sheet material at this stage must be in the form of a uniform and extremely fine mist to avoid spotting of the sheet material which may adversely affect its appearance and/or physical properties.

Within the chamber 15 and along opposite sides of the path of the sheet material 33 are banks of steam coils 45 and 47, each of which includes laterally spaced steam headers 49 which are connected by a series of spaced steam lines or runners 51. Moist steam is delivered into the headers 49 through a steam line 53 and issues from a series of nozzles or jets 55 which project from the runners 51. The steam may be discharged directly against the sheet material 33. Alternatively, as in the case of the very

absorbent and/or extremely fragile materials, the discharged steam may be diffused by being impinged against baffle slats which are supported between the jets 55 and the path of the sheet material.

5 The runners 51 of each bank of steam coils 45 and 47 are preferably inclined upward at their centers to insure that condensation within the respective runners is automatically carried down to the headers 49 and thence out through suitable steam traps 57 and pipes 59. This construction assures that no water can be blown out from the nozzles 55 and thereby prevents water spotting on the sheet material. The chamber 15 is also provided with heating coils 61 and 63 through which steam or other heated medium is circulated. The coils 61 and 63 are 10 designed to maintain the atmosphere within the chamber 15 at a sufficiently elevated temperature to avoid undesired or excessive condensation.

15 Located within the chamber 15, along opposite sides of the exit 31, are suction or exhaust ducts 65 and 57 which are slotted at 69. The ducts 65 and 67 are connected by a pipe 71 to the intake end of a suitable blower or like structure, not shown, and are designed to separate and remove the spent and excess steam and saturated air from along side of the sheet material 33 as it leaves 20 the chamber 15. More important, by exhausting the chamber 15 at its exit end by means of ducts 67 and 69, layers of the applied water mist are drawn into the chamber 15 through its entrance opening 29 and travel concomitantly with and along the opposite sides of the sheet 25 material as it is being subjected to the steam atmosphere. If desired, the heating coils 63 and 65 may extend over portions of the exhaust ducts 67 and 69 so as to avoid 30 undesired cooling and condensation of the moisture carried by the steam within and along areas surrounding 35 such ducts.

40 An atomizer or nozzle 73 is provided outside of the humidifying chamber 15 along one and perhaps both sides of the path of the sheet material 33 as it issues from the exit opening 31. This nozzle 73 is of the same construction as the atomizer 39 heretofore described and is connected by pipes 75 and 77 to suitable sources of water and air or other gas. With sheet materials which are of substantial width a plurality of such nozzles 73 are preferably employed along one and, most usually, along both 45 sides of the sheet material. These nozzles 73 each provide an extremely fine and generally uniform mist or fog of water on or adjacent to the sheet material.

50 In operation, the sheet material 33 proceeds over the guide roll 35 and past the plurality of atomizers 39 where a mist of water is applied on and adjacent to the opposite sides thereof. The sheet material 33 then passes through the entrance opening 29 of the chamber 15 where it is subjected to an atmosphere of moist steam as supplied by the steam lines 53, headers 49, runners 51 and jets 55.

55 The exhaust ducts 65 and 67 and the pipe 71 continuously remove steam from within the chamber 15 and cause layers of water mist to be drawn into the chamber 15 through its entrance opening 29. These layers 60 of water mist travel concomitantly with and along the sides of the sheet material 33 as it is advanced through the chamber 15 and penetrate into the sheet material under the somewhat turbulent and elevated temperature conditions provided by the moist steam atmosphere. The moisture imparted to the sheet material by this water mist is, of course, supplemented by the moisture added by the steam itself so that a substantial amount of water is added to the sheet material during a relatively short 65 treating stage.

70 As the now humidified sheet material 33 issues from the exit opening 31 of the chamber 15, it is cooled by the ambient atmosphere. Alternatively, the humidified sheet material may be more rapidly cooled by means of 75 one or more chill rollers, such as shown at 37.

In lieu of or in addition to the method described above, the sheet material 33 leaving the chamber 15 may be subjected to a mist of water as supplied by the nozzles 73. The sheet material 33 at this stage will be in at least a warm condition and will thus rapidly assume the applied mist of water as the latter travels in a direction opposite to that of the sheet material and toward the exhaust ducts 65 and 67. Since the residual heat of the sheet material 33 is dissipated during this procedure no additional cooling of the sheet material is usually necessary.

As heretofore mentioned, the moisture content of the humidified sheet material 33 is greater when subjected to a mist of water before rather than after such material issues from the chamber. However, when the sheet material 33 is treated with mists of water both as it enters and issues from the chamber 15, and before it has been cooled, its moisture content is greatly and uniformly increased. Moreover, the large addition of moisture to the sheet material by this procedure is not accompanied by water spotting or any apparent sacrifice in the appearance and/or physical properties of the material.

It is to be understood that changes and variations may be made without departing from the spirit and scope of the invention as defined in the appended claims.

I claim:

1. Apparatus for imparting moisture to hydrophilic materials including a chamber having separate entrance and exit openings, means to pass the hydrophilic materials through said chamber, means positioned outwardly of and adjacent to at least one of said chamber openings for applying a mist of water on and adjacent to the materials, steam supply means for subjecting the materials to a steam atmosphere while in said chamber, and suction means located adjacent to the chamber exit opening for withdrawing the steam atmosphere from within said chamber and causing a layer of water mist to be drawn into the chamber through at least one of said chamber openings.

2. Apparatus for imparting moisture to hydrophilic materials including a chamber having separate entrance and exit openings, means to pass the hydrophilic materials through said chamber, means located outwardly of and at least along one side of at least said entrance opening for applying a mist of water on and adjacent to the materials, steam supply means for subjecting the materials to a steam atmosphere while in said chamber, and suction means located along opposite sides of and adjacent to the chamber exit opening for withdrawing the steam atmosphere from within said chamber and causing at least one layer of water mist to be drawn into the chamber through said entrance opening and move with the materials as they travel therethrough.

3. Apparatus as defined in claim 2 further including heating coils disposed within said chamber

4. Apparatus as defined in claim 2 wherein said means for applying the water mist includes an atomizer.

5. Apparatus as defined in claim 2 wherein means for applying a mist of water on and adjacent to the materials are located outwardly of both the entrance and exit openings of said chamber.

6. Apparatus for imparting moisture to hydrophilic materials including a chamber having separate entrance and exit openings, means to pass the hydrophilic materials through said chamber, means located outwardly of and at least along one side of at least said exit opening for applying a mist of water on and adjacent to the materials, steam supply means for subjecting the materials to a steam atmosphere while in said chamber, and suction means located along opposite sides of and adjacent to the chamber exit opening for withdrawing the steam atmosphere from within said chamber and causing at least one layer of water mist to be drawn in a direction opposite to the direction of travel of the hydrophilic materials and towards the chamber exit opening.

7. A method of humidifying a hydrophilic material including the steps of passing the material into a confined humid vaporous atmosphere at one location, removing the material from the confined humid vaporous atmosphere at a location which is separate and spaced from said one location, disposing a fine mist of water on and adjacent to the material outwardly of said confined humid vaporous atmosphere at least at one of said locations, and separating the humid vaporous atmosphere from the material as the material approaches said separate location.

8. A method as defined in claim 7 wherein said fine mist of water is disposed on and adjacent to the material only as it approaches said one location.

9. A method as defined in claim 7 wherein said fine mist of water is disposed on and adjacent to the material only as it leaves said separate location.

10. A method as defined in claim 7 wherein said fine mist of water is disposed on and adjacent to the material as it approaches said one location and also as it leaves said separate location.

11. A method of humidifying a hydrophilic material including the steps of passing the material into a confined humid vaporous atmosphere at one location, disposing a fine mist of water on and adjacent to the material as it approaches said one location, removing the material from the confined humid vaporous atmosphere at a location which is separate and spaced from said one location, separating the humid vaporous atmosphere from the material as the material approaches said separate location, and cooling the material after it is removed from said confined humid vaporous atmosphere.

12. A method of humidifying a hydrophilic material including the steps of passing the material into a generally confined atmosphere of moist steam at one location, disposing a fine mist of water on and adjacent to the material as it approaches said one location, removing the material from the atmosphere of moist steam at a location separate and spaced away from said one location, applying suction at said separate location to remove excess steam and cause a layer of water mist to travel concomitantly with the material as it enters the atmosphere of moist steam at said one location, and cooling the material after it is removed from the atmosphere of moist steam.

13. A method of humidifying a running sheet material including the steps of advancing the sheet material longitudinally of itself through a path, subjecting the sheet material to an atmosphere of moist steam as it is advanced along one portion of its path, applying a fine mist of water on and adjacent to the advancing sheet material as it approaches and enters the atmosphere of moist steam, separating the moist steam atmosphere from the sheet material by suction at a location which is separate and spaced from the location at which such sheet material enters the moist steam atmosphere and thereby cause at least one layer of water mist to be drawn with the sheet material as it enters and is advanced through the atmosphere of moist steam, and applying a fine mist of water on and adjacent to the advancing sheet material as it leaves the location at which it is separated from the moist steam atmosphere.
